METHOD FOR RENOVATING JOURNAL BOX PACKING

Application filed August 23, 1930. Serial No. 477,442.

The invention disclosed in this application relates to the method for renovating journal box packing.

The object of the present invention is to improve the method of all previous known methods of renovating journal box packing and aims to more effectively and uniformly remove substantially the entire undesirable contents of the packing including the lint part before being again united with the lubricating oil.

It is now a well recognized fact in the art of renovating journal box packing that it contains undesirable finely divided lint coming from the fibers of the waste part and carried in the oil part. It also contains other undesirables such as sand, grit, dirt of all kinds, pieces of metal, and water. The water may be in suspension in the oil in the form of globules, or it may be soaked up by the fibers, and sometimes it is in the form of ice. It is essential therefore in the renovation of the packing to remove all these undesirables and restore the waste part to as nearly its original condition as possible and the oil part so that it at least is as good as new oil. This entails the separation of the waste and oil parts, and such separation is only effected when the viscous oil of the packing is rendered fluid and the water content is removed. It has been found that the water content is a very disturbing element in that some agitation must take place in the removal of the oil and such agitation and heat in itself, and in the presence of the dirt, tends to produce an emulsified condition which hinders the removal of the other undesirables. It also interferes with the initial heating of the mass of packing in that it prevents the effective, free and rapid circulating medium. Heretofore the necessary step of heating has been accomplished by soaking methods of one kind or another but such practices do not uniformly and forcibly pass the hot heating medium through all the interstices and about all the fibers, a step necessary for the uniform removal of the water content and the later uniform separation of the waste and oil parts.

The object of the present invention therefore is to provide a method for renovating journal box packing wherein the separation of the waste and oil parts is more effectively accomplished than heretofore by uniformly and forcibly circulating through the interstices and about the fibers of the dirty packing an anhydrous dehydrating medium at a temperature sufficient to vaporize and quickly drive off, in the early stages of the process, substantially the entire water content. The washing medium or oil is therefore free to carry off with it substantially the undesirable entire lint content of the waste, much of the other undesirables, except possibly the larger particles, and leave the waste part and oil substantially dehydrated so that later impregnation may be effectively accomplished and so that the circulating or washing medium also is left substantially devoid of water moisture and ready for further use or treatment by the oil renovating step of the method. Such steps of the method materially assist in the proper and effective renovation of the oil which accumulates from time to time and must be treated to render it as far as possible like new oil.

Specifically the method will best be understood by reference to the apparatus.

The first piece of apparatus employed is the oil washing and removing means and is an extractor of the familiar type preferably underdriven and having the usual basket with a reticulated or foraminous outer peripheral wall, with the usual inwardly extending upper flange for preventing the escape of material through the central opening therein. The inner wall of this basket, however, is provided with a reticulated inner lining, not of the usual flat wire mesh type, but of similar material arranged in saw tooth arrangement in cross section with the edges of the teeth, so to speak, extending vertically. In other words there are vertical ridges and valleys around the inner periphery of the basket so that triangular ridges of reticulated material extend into the basket space and hence into the packing. This extractor is also provided with suitable oil distributing

means of a type such that uniform distribution of oil supplied by it to the packing within the basket will be distributed evenly throughout all horizontal cross sections of 5 the basket and the packing therein. Such a device may be in the form shown in the drawings of the cylindrical distributor type having vertical slots varying in width from bottom to the top with the narrow ones at the 10 bottom. The curb of this extractor is provided with the usual drain so that the washing medium or lubricating oil does not accumulate in the curb but passes out of the sump or storage as will appear.

15 In utilizing this piece of apparatus, after it has been charged with the dirty inbound packing, it is rotated at approximately 900 R. P. M. and hot washing medium, such as hot lubricating oil is supplied to the distributor 20 at the center of the basket. The speed of the basket during this washing operation is preferably such that the resulting centrifugal force upon the inbound dirty oily packing is insufficient to result in the packing or 25 matting of the material against the outer wall of the basket so that free circulation of this washing medium through the packing is possible at all times. But on the other hand, 30 such speed should lend itself very nicely to uniform, forcible and free circulation of the washing medium through the packing. In addition to this speed feature just described the saw tooth arrangement of the interior of 35 the basket forms such a large foraminous outer supporting surface for the annulus of packing and extends into the packing in such a way that free circulation through the material is not hampered but on the other hand is enhanced. The waste part does not have 40 a chance to compact itself against the ridges and the valleys between them to the extent of interfering with the free circulation. Indeed in the prior ordinary straight, non-undulating type of outer basket wall the material 45 impinges so tightly against it that the oil has difficulty at the blank areas passing through the adjoining packing to the openings. All of this is done away with in this saw tooth arrangement and free removal of 50 the oil from the parts of the packing and all parts of the basket is produced.

55 The washing medium is preferably anhydrous and is at a temperature sufficient to vaporize moisture so that substantially the entire undesirable lint content of the packing is removed and remains in the oil and the moisture content is also removed by 60 passing off into the atmosphere. In the case of the lint it goes with the oil, in the case of the moisture it escapes as vapor. By this operation the emulsified condition of the entire product including the waste and oil parts is materially reduced because of the fact that at the low speed of washing there is insufficient agitation. This hot oil washing is pref-

erably continued for a sufficient length of time to remove substantially all of the moisture. The washing medium or oil is maintained at the proper temperature by any suitable regulating means for the purpose, the main point being that it should be, as stated, at a temperature sufficient to vaporize and permit the removal of the entire moisture content. After the washing step has been performed the extractor is then speeded up to approximately 70 1800 R. P. M. when substantially all of the washing medium yet remaining in the packing as well as any of the original oil, yet contained therein, is removed leaving the waste part in a state of uniform fiber saturation 75 without deposits of lint carrying oil in the interstices of the waste part and with substantially all of the lint content removed and in the oil.

80 The waste part which is now in the condition of fiber saturation only is then removed and preferably is placed in a tumbler of any of the well-known types, or on a picking table, or on any suitable apparatus which may be utilized for removing, as by picking, 85 or by tumbling, or by agitation, the other undesirables in the waste part, as for example, sand, grit, dirt, metal fragments, and the like. While this cleaning step just described is beneficial for the purpose mentioned, it is not essential in all cases and to 90 all phases of the invention herein.

95 The washing medium is hot, as stated, and heat may be supplied to it to bring it up to the proper temperature by many devices suitable for the purpose, such as an indirect heater including a circuit for the washing medium and a primary heating circuit connected to a steam or other heat supply.

100 While the treatment of the packing is going on, as above described, quantities of the washing oil may be withdrawn from a suitable sump or other container and conveyed to oil renovating apparatus of any suitable type capable of handling an emulsified oil and one 105 containing lint. Such an oil renovator must remove all traces of lint which is the disturbing factor and the hot box forming medium of journal box packing. This lint is not readily removed from an emulsified oil, hence 110 this oil renovating plant must be capable of 115 handling such an oil.

120 This oil step is improved by prior treatment herein disclosed in that the emulsified condition of the oil is greatly reduced.

125 As batch after batch of inbound dirty packing is treated in the manner just described, batches of the accumulating oil will be treated and when renovated batches of the waste part and quantities of the oil part have been renovated they may be brought together to provide not only a renovated packing, but one which is even better than a packing made from new oil and new waste.

130 The various features of invention already

enumerated and others will be brought out in the following description, drawings and claims:

In the drawings, Fig. 1 is a top plan view 5 of a portion of the plant, including a drip board arrangement and the extractor or washing and oil removing means; Fig. 2 is a front elevation of the apparatus shown in Fig. 1; Fig. 3 is a top plan view of a portion 10 of the extractor basket with a portion in section; Fig. 4 is a view in side elevation with parts broken away; Fig. 5 is a vertical section through the oil distributor; Fig. 6 is a section upon the line 6—6 of Fig. 5; Fig. 7 is a section 15 upon the line 7—7 of Fig. 5; and Fig. 8 is a diagrammatic view of the entire plant.

As above indicated, the plant includes what might be termed two parts, one the oil removing and waste renovating part, and the 20 other the oil renovating part.

The former preferably includes a pair of extractors spaced apart with a drip tank and board arrangement therebetween, and such apparatus includes the extractors 1 and 2 25 both alike and of the now familiar under-driven type with the curb of each provided with suitable drains 3 leading to any suitable sump or other receiver for the extracted or removed oil. As stated, these extractors are 30 of any approved type except that the basket of each includes the usual bottom 4, a perforated side wall 5, and the upper flange 6. Within the perforated side wall is what has been termed a "saw tooth lining" of reticulated material such as wire mesh bent to form 35 vertical V-shaped ridges 7 and valleys 8 between these ridges. These ridges obviously extend into the basket space and hence likewise extend into any mass of material deposited in the basket. This ridge and valley arrangement furnishes a maximum of reticulated discharge packing supporting surface 40 for the packing as it is thrown outward by centrifugal force against it. These ridges not only increase the available reticulated surface 45 for the discharge of oil from the packing, but also prevent the undue packing or matting of the packing against this surface. Furthermore, in such an arrangement 50 straight imperforate wall portions are not set up in direct opposition to the normal travel by centrifugal force of the oil through the basket. Hence the oil readily finds its 55 way through this ridged lining and easily escapes through the outer wall of the basket.

In the arrangement shown in Figs. 5, 6 and 7, the center of the basket is preferably provided with a cylindrical distributor 9 60 preferably having a symmetrically arranged group of oil distributing slots or openings 10. These openings must be symmetrically arranged in order, as far as possible, to evenly distribute the oil against the breast or inner surface of the annulus of packing as it is 65 formed in the basket. They must also be

graduated in size from the bottom to the top with the smaller ones at the bottom so that both the weight of the oil and the effect of centrifugal force on the oil will both produce a uniform supply from top to bottom against the breast or inner face of the annulus of packing. It is preferable to have the upper end of the cylinder provided with an inwardly extending flange 11 to prevent the escape 70 of the oil as it rises in the cylinder in the formation of its meniscus. Oil may be supplied to this cylinder in any suitable manner as through the opening 11' from a pipe connected with the hot washing oil supply.

In the use of the extractors equipped in this way it is started rotating at slow speed, say 900 R. P. M., when some of the oil content of the packing will tend to flow out in spite of its cool condition. Hot washing medium such as lubricating oil ranging in temperature approximately at 212°, or whatever is necessary to vaporize the water content is then supplied to the distributor and caused to impinge with force against the breast or inner surface of the annulus of packing, driving the old dirty oil out ahead of it and washing the fibres clean of not only dirt content but substantially the entire lint content, the lint of course remaining with the oil and the dirt settling if it can in a suitable sump in the oil circuit. The heat of the oil must be sufficient to vaporize substantially the entire water content in order to leave both the waste part and the oil part, as far as possible, free of any moisture. After the washing step has been performed and the supply of washing oil ceases, the extractor is then speeded up to approximately 1800 R. P. M. when the removal or extraction of all oil in the waste is effected, thus leaving the waste part devoid of any oil deposit in its interstices and with fiber saturation only.

One important phase of the invention herein is the substantial elimination of moisture not only from the waste part but also from the oil body in that, as stated, the emulsified condition of the oil is, if not entirely, very materially reduced. It has been found that the presence of this emulsion, either water in oil or oil in water, tends to limit the extent of 110 lint removal so that by quickly removing the moisture in the initial washing stage of the renovating process more effective lint removal is accomplished.

While the inbound dirty packing may be charged into the extractors directly from the inbound barrels or other containers it is preferable to use a drip tank arrangement in conjunction with the extractor or extractors, and such an arrangement may be like that 125 shown in the drawings, Figs. 1 and 2, wherein in a tank 12 is provided having an upper grating 13 just below the top of the extractor curbs and connected by drain boards 14 to the top or tops of the extractors. This tank 130

12 will be connected, as will appear, to the oil renovating plant. A suitable hoist 15 may be provided for elevating the barrels or containers to a position where the contents 16 may be dumped upon the grating 13. In use, the inbound dirty packing in barrels or containers is dumped on the grating and allowed to drip while it is waiting its turn to be charged into the extractor. In the arrangement shown the drip tank arrangement is arranged between two extractors which is a very convenient and efficient arrangement for speedily handling a large volume of journal box packing.

17 As stated, the waste part when reduced to fiber saturation only may be treated in a tumbler or other agitating device for the removal of undesirables other than the lint which has been taken up by the washing medium. Such a device may be a tumbler, generally indicated at 16, and of the type shown in the patent to Dewey 1,488,198, issued March 25, 1924. Such a tumbler is well known in the art and usually includes an 20 outer casing provided with optional heating means and provided with a door providing access, and also with optional air circulating means. It is also provided with an inner tumbling barrel rotated in opposite directions and receiving the load of fiber saturated waste after its prior treatment. This inner drum is reticulated so that undesirables such as dirt, metal parts, short ends, relatively 25 large pieces of lint, or fiber may be shaken 30 out. In this step any moisture not previously removed from the waste part may be driven off.

After treatment in such a device the fiber saturated waste part may then be impregnated with new or renovated oil. Such an 40 impregnator is shown in my prior Patent 1,723,747, granted August 6, 1929.

An impregnator of this type includes a container or tub in which is placed the proper 45 quantity of new or renovated oil and the proper quantity of renovated waste for taking up such quantity of oil. The renovated waste is dumped into the oil and a suitable piston cover is inserted in the tub or container and a vacuum applied so that the cover moves down and produces the immersion of the waste in the oil with the extraction by the 50 vacuum of any entrained air or vapor present.

The oil for the extractors 1 and 2 as well as 55 for the drip tank 12 is handled by suitable tanks and piping which will now be described. At a suitable low level is a combination sump comprising the washing oil tank portion 17 and the dirty oil tank portion 18, separated 60 by a suitable wall 19. The tank 17 is utilized for the washing medium, while the tank 18 is utilized as a sump for the dirty oil coming from the drip tank 12 as well as from the extractors 1 and 2. This latter tank 18 is provided with a partition 20 rising from the bot-

tom to a suitable height so as to provide a settling chamber to the left and a drainage chamber 21 to the right. This drainage chamber 21 is connected to a suitable drain pipe 22. The tank 17 is also provided with 70 a drain pipe 23.

Leading from the extractors 1 and 2 is a pipe 24 branching into a pipe 25 provided with a valve 26 and into a pipe 27 provided with a valve 28. This pipe 27 is also 75 branched to a pipe 29 connected to the drain pipe 30 leading to the drip tank 12. This pipe 29 is provided with a valve 31 and branches into another pipe 32 provided with a valve 33 and leading to the waste reclamation plant together with the pipes 22 and 23. The pipe 27 with its branch 29 lead to a three-way valve structure 34 connected to a pipe 35 leading to the washing oil tank 17 and another pipe 36 leading to the dirty oil tank 18 to the left of the partition or wall 20. By the proper manipulation of these valves all dirty oil may be conveyed to the dirty oil sump 18 to the left of the partition 20 or to the washing oil portion 17, extending down into both of the 80 tanks 17 and 18 from outlet pipes 37 and 38 respectively, each provided with a valve 39 and leading to a pipe 40 connected to the intake of a pump 41. This pump has its delivery 42 connected to the secondary circuit 85 of an indirect heater, generally indicated at 43, the outlet of this secondary circuit being connected to a pipe 44 provided with a valve 45 and leading to the opening 11' of the oil distributor in the extractor. The primary circuit including the pipes 46 and 47 may be connected to any suitable source of heat supply, such as a steam line or the like. In one of these pipes, as for example the pipe 47, is a pressure regulator, of any well known 90 type and generally indicated at 48 and of a type such that it may be adjusted to regulate pressures of steam and hence the temperature of the oil passing through the secondary circuit. This regulator is used to determine the temperature of the oil delivered to the packing in the extractor. Leading from the pipe 40 is a circulating pipe 49 provided with a valve 50 and leading to a circulating tank 51 which receives oil from the pipe 25, this oil coming from the extractors 1 and 2. Pipe 40 is also connected to another pipe 52 leading to the oil plant.

In use the dirty oil coming from the drip tank 12 may be directed into the dirty oil tank 18. Likewise, the dirty oil from the extractors at the beginning of the operation may be drained into this tank. As this dirty oil accumulates it may be circulated through the extractors by proper manipulation of the valves by means of the pump 41 or it may be allowed to settle in this tank 18 until it overflows the partition 20 when it will drain through the pipe 22. When washing oil collected in the tank 17 is to be utilized it is 100 105 110 115 120 125 130

drawn through the pipe 37 through the pump 41, through the heater 43, and projected into the distributor in the extractors. When this washing oil in the tank 17 becomes too foul for further use it may be drained through the pipe 23 to the oil renovating plant. When new oil is to be used for washing the valve 52' in the pipe 52 is opened and other valves manipulated so that new oil or renovated oil from the oil plant is circulated through the pump 41, heater 43 to the extractor. Either the washing oil from the tank 17 or clean oil from the oil renovating plant may be recirculated through the extractors by the circuit including the pipes 25, tank 51, pipe 40, pump 41, etc.

The pipe 22 leads to another sump 53 which is provided with an outlet pipe 54 having a valve 55 and connected to the inlet of a force pump 56, the outlet 57 of which leads to the oil plant. Pipe 54 is connected to the pipe 23 which has a valve 58 therein. Pipe 54 is also connected to the pipe 32 which branches off from the pipe 30 leading to the drip tank 12.

From the foregoing it will be seen that the dirty oil from the drip tank, the dirty oil from the dirty oil sump 18, as well as the washing oil from the tank 17 may be disposed of through the pump 56 and delivered to the oil plant.

The renovation of the oil during the various steps of the process may be accomplished by any suitable form of apparatus capable of handling an emulsified or a partially emulsified oil and one containing lint and other undesirables, such as are present in the oil of journal box packing. Such an apparatus is disclosed in the applications of Leonard D. Grisbaum, Serial No. 74,979, filed December 12, 1925, method of and apparatus for reclaiming oil; and Serial No. 210,545, filed August 4, 1927, oil reclamation.

The renovating plant includes three tanks D, E and F interconnected and performing the several oil renovating steps, as will appear.

Tank D has a cylindrical body and conical base to the bottom of which the pipe 57 is connected. It is provided with a jacket 59 in which is a steam heating coil 60. At the top of the tank are one or more spray nozzles 61 communicating with a hot water pipe 62 from the tank 63. This pipe 62 also communicates with the jacket 59 by a pipe 64 to supply hot water thereto. Both of these pipes 62 and 64 are provided with valves, generally indicated at 65. In the tank D is placed a charge of a solution of a suitable alkali, such as caustic soda. Water is supplied to the jacket and steam is passed through the heating coils 60 to raise the temperature even to a point above boiling, the water supply pipes being shut off to hold the water under pressure. The oil to be

cleaned is then admitted to the bottom of the tank and bubbles up through the alkali solution, producing a sufficient agitation for the treatment. When a sufficient quantity of oil has been admitted the tank is allowed to stand for an appreciable time, say five hours, at this higher temperature, and the heating under pressure stimulates the mixing action. Finally, the valve 65 in the water supply, which comes from the open tank 63, is opened, relieving the pressure in the jacket and permitting the temperature to drop to approximately boiling, in which condition the tank is maintained for another period of about five hours. The cover is now removed from the tank and hot water is sprayed onto the surface of the oil through the nozzles 61. This spraying is continued to thoroughly wash the oil. All soluble matter goes into solution and stays with the water, and the solid matter, including dirt particles, which may have been suspended in the oil, is carried down and settles with the sludge. The oil has a lower specific gravity and floats on the top of the water, while the sludge collects at the bottom. There are now three layers in tank D—first, at the top there is clean oil containing traces of chemicals and water; second, the water; and third, the sludge.

The continued heating in tank D prior to the spraying or washing with water breaks down or destroys part of the lint, such as the woolen or animal fibers, and precipitates the remainder, such as cotton or vegetable fibers. It also produces chemical reactions with chemical impurities, such as soaps, grease and the like, and makes them either soluble or precipitates them. As a consequence, when the water washing step has been performed the oil in the top layer is free of lint and mechanical impurities and contains but a small portion of chemical impurities with the moisture or water in it.

The oil in the upper layer is now drawn off through the pipe 66 and supplied thereby to a perforated pipe 67 at the bottom of tank E, which is filled with hot water. In said tank the oil rises in a greatly broken up condition and accumulates above the water level and below a hollow plate 68 heated by steam circulated through it by the pipe 69. Said plate is of bell form with a center opening or mouth and is preferably kept heated at about 250° F. As the rising oil strikes it any water entrained in it is vaporized and escapes. Above the hollow plate 68 is a cone 70 with a center opening 71. As the oil accumulates it finally flows out through the center opening 71 and down the sides of the cone 70 to a pipe 72 by which it is supplied to the tank F.

I claim:

1. The herein described steps of a method of renovating journal box packing made up of a fibrous waste part and an oil part, which

steps consist of the step of placing the packing in a perforated container; the step of thereafter slowly rotating said container and during such rotation, delivering heated
5 cleansing oil into said container for entry into said packing, the rotation of said container during said oil delivery effecting better distribution of said oil into said packing and the slow speed of such rotation preventing
10 undue matting or compacting of said packing; and the step of thereafter rapidly rotating said container to cause an appreciable portion of the oil in the packing to forcibly pass therethrough and leave said container through the perforations thereof.

2. The herein described steps of a method of renovating journal box packing made up of a fibrous waste part and an oil part, which steps consist of the step of placing the packing in a perforated container; the step of thereafter slowly rotating said container and during such rotation, delivering into said container for entry into said packing cleansing oil heated to a sufficient degree to vaporize any moisture in said packing, the rotation of said container during said oil delivery effecting better distribution of said oil into said packing and the slow speed of such rotation preventing undue matting or compacting of said packing; and the step of thereafter rapidly rotating said container to cause an appreciable portion of the oil in the packing to forcibly pass therethrough and leave said container through the perforations thereof.

3. The herein described steps of a method of renovating journal box packing made up of a fibrous waste part and an oil part, which steps consist of the step of heating the packing by passing heated oil therethrough while said packing is supported in the perforated basket of a centrifugal extractor and is not subjected to appreciable centrifugal force; the step of thereafter rotating said basket at a high speed to remove from the packing therein as much as possible of its oil; and the step of thereafter loosening the fibres of the waste part of said packing.

4. The herein described steps of a method of treating fibrous waste for use in journal boxes, which steps consist of the step of placing the waste in a container; the step of preheating oil to a moisture vaporizable degree; the step of delivering said oil in such preheated condition to said container for entry into said waste, thereby vaporizing the moisture in said waste; and the step of thereafter causing, while said waste is in said container, an appreciable portion of the oil in said waste to forcibly pass through and out of said waste and out of said container.

In testimony whereof I hereby affix my signature.

EDWIN S. PEARCE.
